UNITED STATES PATENT OFFICE.

ERNEST J. SMITH, OF NEW YORK, N. Y., ASSIGNOR TO R. HOE AND CO., OF NEW YORK, N. Y., A CORPORATION OF NEW YORK.

INKING MECHANISM.

1,289,011.

Specification of Letters Patent. Patented Dec. 24, 1918.

Application filed January 29, 1916. Serial No. 74,984.

To all whom it may concern:

Be it known that I, ERNEST J. SMITH, a subject of the King of England, residing at New York, county of New York, and State 5 of New York, have invented certain new and useful Improvements in Inking Mechanism, fully described and represented in the following specification and the accompanying drawings, forming a part of the same.

10 This invention relates to certain improvements in inking mechanism for printing machines.

It is the especial object of the invention to provide an improved mechanism particularly for high speed rotary printing machines in which the construction shall be simple as compared with previous mechanisms, and in which the parts are easily accessible and so constructed as to facilitate 20 the adjustment of the ink supply, which is particularly desirable in such machines, especially where the inking mechanism is used with an extra couple for printing late news, which is often placed in more or less 25 inaccessible positions in the machine.

With these and other objects in view, the invention consists in certain novel parts and combinations which will be described in connection with the accompanying drawings, 30 to afford a full understanding of the invention. The figure is a side elevation of one side of the machine illustrating the improved inking mechanism.

Referring now to this drawing, the inking mechanism is shown in connection with a rotary press, the form cylinder of which is indicated by the numeral 1, the remainder of the press not being illustrated, as such illustration is not necessary for an understanding 35 of the invention. Coöperating with the form cylinder 1 is the usual form roll 2. In machines embodying the invention in its best form, this form roll 2 is supported so that its pressure on the form cylinder may be varied within desired limits. While the means for thus supporting this roll may be somewhat varied, in the particular construction illustrated this form roll 2 is supported in suitable bearings in frames 40 45 50 55 60 65 70 75 80 85 90 95 100 105 110 3, only one of which is shown, these frames being pivotally mounted at 4 in brackets 5 rigidly secured to the main frame 6 of the machine. The frames 3 are adjusted and held in position to give the desired pressure of the form roll 2 on the form cylinder 1 in

any suitable manner, as by means of set screws 7, 8 provided with lock nuts 9, 10, these set screws being fitted in the fixed brackets 5 and disposed at right angles to each other so as to afford an up and down adjustment of the pivoted frames 3, the screw 7 taking against the bottom of the frame for affording a vertical adjustment, and the screw 8 taking against a shoulder 11 formed in the end of the frame and holding the frame rigidly in adjusted position. The form roll 2 is a driven roll, being driven in any suitable manner, as from the form cylinder through intermediate gearing 12, 13.

The form roll 2 takes ink from the ink supply and delivers it to the form cylinder 1. In machines embodying the invention in its best form, means are provided whereby the ink may be delivered from the fountain or other source of ink supply to the form roll without the employment of the usual lifter roll, thus simplifying the construction. While these means may vary somewhat in construction, in the particular construction illustrated this is effected by means of an ink fountain 14 provided with a fountain roll 15 mounted in the fountain so as to be normally in close proximity to but not in contact with the form roll 2. This ink fountain is furthermore mounted so that it may be given an intermittent movement to bring the fountain roll into contact with the form roll so as to supply an intermittent amount of ink thereto. While this movement and the means for effecting it may be somewhat varied, in the particular construction illustrated this movement is a rocking or oscillating movement, the fountain 14 being pivotally supported on studs 16 on the pivoted frames 3, before referred to, and is normally held so that the fountain roll 15 is just clear of the form roll 2, this being accomplished in any suitable manner, as by the spring 17. The rocking or oscillating movement is effected in any suitable manner. In the particular construction illustrated, the shaft of the fountain roll 15 is provided with a cam disk 18, which preferably is provided with two lifting cam portions 19, so that the fountain will be rocked and the fountain roll be brought into contact with the form roll twice every time the fountain roller makes a complete revolution. The cams 19 coöperate with a suitable

cam surface for effecting the rocking of the fountain which, in the particular construction shown, is a fixed bowl 20 mounted in an extension 21 of the pivoted frame 3, before referred to. In the best constructions, this fixed bowl 20 is adjustable to effect an easy and quick adjustment in the amount of rocking movement given to the fountain. While this may be accomplished in various ways, as illustrated the bowl 20 is eccentrically mounted in arms 22 supported on the extension 21 before referred to. By simply loosening the securing nuts 20' and partly rotating the bowl, more or less of a rocking movement may easily be given the fountain, and the extent of movement or depression of the fountain roll correspondingly easily adjusted.

The fountain roll is driven in any suitable manner, as by means of the bevel gears 23 driven from a shaft 24, in turn driven through worm gear 25 from the shaft 26 of the form roller 2, before referred to.

Machines embodying the invention will also be provided with two distributing rollers 27, which preferably will be of metal, mounted in slots 28 formed in the swinging frames 3 before referred to and resting on the form roller, and preferably a composition roller 29 will be provided mounted in the frame 3 above the metal rollers and resting thereon. In the best constructions, this roller 29 will have a reciprocating movement imparted to it, which may be effected by means of the usual levers 30 and crank pin 31 on the end of the shaft 24 before referred to.

With the mechanism described ink may be supplied from the fountain to the form roll without the employment of the usual lifter roll and the mechanism for driving it. Furthermore, the amount of supply is easily regulated by adjusting the amount of rocking movement imparted to the fountain roll, and furthermore the pressure of the form roll on the form cylinder is likewise readily adjustable, and the means for effecting the various adjustments are all readily accessible, which is a great advantage in inking mechanisms of this class.

While the invention has been shown and described in its preferred form, it will be understood that various changes may be made in the specific forms of mechanism shown and described, and that the invention is not to be restricted to such forms.

What is claimed is:

1. In an inking mechanism for printing machines, the combination with a form roll, of an ink fountain mounted to have a tipping movement, a fountain roll rotating in the fountain and in close proximity to the form roll, a cam on the fountain roll, and a co-operating cam surface for oscillating the fountain on its pivot to bring the foun-

tain roll intermittently into contact with the form roll.

2. In an inking mechanism for printing machines, the combination with a form cylinder, of a form roll for distributing ink to the cylinder, a pivoted frame in which the form roll is carried, means for adjusting the frame to vary the pressure between the form roll and the cylinder, an ink fountain mounted on the frame from which ink is delivered to the form roll, and means for effecting a movement between the fountain and the form roll for causing an intermittent supply of ink to be delivered thereto.

3. In an inking mechanism for printing machines, the combination with a form cylinder, of a form roll for distributing ink to the cylinder, a pivoted frame in which the form roll is carried, means for adjusting the frame to vary the pressure between the form roll and the cylinder, an ink fountain pivoted on the frame from which ink is delivered to the form roll, and means for oscillating the fountain on its pivot to bring the fountain roll into intermittent contact with the form roll.

4. In an inking mechanism for printing machines, the combination with a form cylinder, of a form roll for distributing ink to the cylinder, a pivoted frame in which the form roll is carried, means for adjusting the frame to vary the pressure between the form roll and the cylinder, an ink fountain pivoted on the frame, a fountain roll rotating in the fountain, and a cam and a co-operating cam surface for oscillating the fountain roll on its pivot to bring the fountain roll intermittently into contact with the form roll.

5. In an inking mechanism for printing machines, the combination with a form roll, of an ink fountain mounted to have a tipping movement, a fountain roll rotating in the fountain and delivering ink to the form roll, a cam on the fountain roll and co-operating cam surface for causing an intermittent contact between the form roll and the fountain roll, said cam surface being adjustable for adjusting the amount of oscillation of the fountain.

6. In an inking mechanism for printing machines, the combination with a form cylinder, of a pivoted frame, a form roll mounted in the frame, means for adjusting the frame for varying the pressure between the form roll and the form cylinder, an ink fountain pivoted in the frame, a fountain roll rotating in the ink fountain and acting to deliver ink to the form roll, means for rocking the fountain to cause the fountain roll to have an intermittent engagement with the form roll, and means for varying the amount of the rocking movement.

7. In an inking mechanism for printing presses, the combination with a pivoted

frame, of a form roll mounted in the frame, a fountain, a fountain roll rotating therein, a pair of metal distributing rolls contacting with the form roll, a composition distributing roll contacting with the metal distributing rolls, and means operated from the form roll shaft for driving the fountain

roll and for giving the composition roll a longitudinal movement with respect to the metal distributing rolls.

In testimony thereof, I have hereunto set my hand.

ERNEST J. SMITH.
